UNITED STATES PATENT OFFICE.

FRED L. MACKENZIE, OF BEVERLY, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

CHANNEL-OPENING DEVICE FOR FASTENING-INSERTING MACHINES.

1,375,795.

Specification of Letters Patent. Patented Apr. 26, 1921.

Application filed October 13, 1917. Serial No. 126,353.

To all whom it may concern:

Be it known that I, FRED L. MACKENZIE, a citizen of the United States, residing at Beverly, in the county of Essex and State of Massachusetts, have invented certain Improvements in Channel-Opening Devices for Fastening-Inserting Machines, of which the following description, in connection with the accompanying drawings, is a specification, 10 like reference characters on the drawings indicating like parts in the several figures.

This invention relates to devices for opening a channel in the work in advance of mechanism arranged to operate on the bottom 15 of the channel and more particularly to a channel opening device constructed and arranged to expose the bottom of a channel formed in a shoe sole to the operation of mechanism for inserting metallic fastenings 20 therein to make a seam in the sole. The invention is herein illustrated as embodied in a machine for inserting fastenings of the type shown and described in United States Letters Patent No. 1,030,775, granted June 25, 1912, on an application of George Goddu.

In the operation of machines of the type shown in the patent above cited in nailing in a channel, an awl is forced downwardly into the channel to form an opening to receive the fastening, and is then moved transversely of its work penetrating movement to feed the work. Its feeding movement being completed, the awl is withdrawn from the work, and a fastening delivered 30 into the opening formed by the awl and driven into the work. In the meantime, the awl is again forced into the work, and the operations above set forth are then repeated to make a seam of metallic fastenings in the 35 bottom of the channel.

Difficulty has been experienced in the operation of such machines, for example, by reason of the entrance of the awl in the channel not being effected readily and properly and by reason of the breaking down of the channel lip by the awl.

It has previously been proposed to provide means for opening the channel in advance of the entrance of the awl in the channel, but the operation of such devices has not been entirely satisfactory. In the operation of prior constructions on portions of the work in which the distance between the edge of the work and the inner edge of the

channel is greater than normal, the inner 55 edge of the channel may be drawn away from the part of the channel opening means which directly engages the channel or the channel engaging part may be otherwise displaced relatively to the channel to an extent 60 such that its effective operation is prevented. Moreover, the channel opening means of certain of such devices is liable to be forced against the inner edge of the channel particularly in operating around a curved 65 part of a shoe sole such as the toe, in such manner as to mutilate the channel lip or other portion of the sole adjacent to the channel.

One of the objects of the present invention 70 is to provide channel opening means so constructed that the above-mentioned and other difficulties may be obviated.

In accordance with an important feature of the invention, means are provided in combination with the fastening inserting instrumentalities or other mechanism for operating on the bottom of a channel formed in the work being operated upon, constructed and arranged to lie in and turn back the 80 lip of the channel in advance of the operation of the operating means and movable by the work in a direction parallel to the plane of the work and transverse to the plane of operation of the operating means. Operative engagement of the channel opening means with the inner edge of the channel is thus insured regardless of the displacement of the inner edge of the channel relatively to the plane of operation of the operating 85 means resulting from movement of the work or from a change in the distance between the edge of the work and the inner edge of the channel.

The part of the channel opening means 95 which directly engages the channel, in addition to the movement above mentioned, is also capable of being moved by the work in a direction transverse to the plane of the work and parallel to the plane of operation 100 of the operating means or in a direction compounded of the above-mentioned directions of movement. The channel opening means is thereby caused to maintain proper engagement with the channel in any position 105 of the work and independently of the shape of the work or of the character of the channel formed therein.

In the preferred embodiment of the invention, the channel opening means is mounted loosely on a stationary support so as to bear a constant relation to the point 5 of operation of the operating means on the bottom of the channel to the end that the channel engaging part of the channel opening means may engage the channel lip closely adjacent to the point at which the 10 awl or other operating means operates on the bottom of the channel, and is movable to accommodate itself to the requirements of the work being operated upon.

Certain of the mechanical features of the 15 preferred embodiment of the invention may be substituted for by equivalent mechanism without departing from the essentials of the invention. A modification of the invention possessing important advantages of the preferred embodiment thereof will be herein- 20 after described.

Although the invention is hereinafter described as embodied in fastening inserting machines of the type shown in the patent to 25 Goddu above cited, it is recognized that the applicability of the invention is not limited thereto.

Other objects and novel features of the 30 invention will appear as the description proceeds.

In the drawings:

Figure 1 is a front elevation of the head 35 of a machine of the type disclosed in the patent above cited, showing the preferred embodiment of the present invention applied thereto;

Fig. 2 is a plan view of the channel opening device of this invention mounted on the guard plate of the machine;

Fig. 3 is a view in elevation looking from the right of Fig. 2;

Fig. 4 is a view in cross-section on the line 4—4 of Fig. 2, looking in the direction of the arrow, and showing further a cross-section of the work;

Fig. 8 is a plan view of the modification shown in Fig. 7;

Fig. 9 is a view in elevation looking from the right in Fig. 8 and showing the awl bar carrier in cross section, and

Fig. 10 is a cross section on line 10—10 of Fig. 8 looking in the direction of the arrow.

The illustrated machine has a supporting frame including a standard or column 2 and a head 4. In the column 2 is mounted the work support or horn 6, (see Fig. 4) the 65 machine being provided with suitable mech-

anism for operating the work support between work receiving and work clamping positions and for automatically depressing the work support periodically during the operation of the machine to release the work feeding movements, which mechanism may conveniently be as shown and fully described in said Letters Patent.

In the machine head 4 are mounted the various parts of the fastening inserting 75 mechanism and the cams which control the timing of the operations of the various parts of the machine as a whole.

The fastening inserting or fastening driving mechanism comprises a driver bar 8 mounted to reciprocate vertically in a guide-way in an upright part of the machine head and having clamped to its lower end a driver 10. The driver 10 reciprocates in a driver passage in a fixed driver guide 12. 80 Upon its rear side the driver bar 8 is provided with rack teeth engaged by the teeth of a segment rack carried upon a cam operated lever (not shown).

The fastenings to be driven are contained 90 in a hopper (not shown) from which they are conducted by a raceway 14 to a point adjacent to the driver passage in the driver guide 12, said guide being broken away at the side adjacent to the raceway whereby 95 the fastenings may be introduced one at a time from the raceway into said driver passage.

Below the driver guide 12 is a fastening receiving throat 16 mounted upon a throat 100 carrier or slide 18 and movable with said slide transversely to the path of feed of the work and transversely to the raceway 14. Transverse movement of the throat 16 is provided for the purpose of withdrawing 105 the throat from the path of shoe feed movement of the awl 20, hereinafter further referred to, in order to permit the awl to bring the fastening receiving opening which it has formed in the work beneath the driver passage in the throat 16. The throat carrier or slide 18 is guided in an opening in the machine frame and is provided at its rear end with rack teeth with which engage 110 teeth upon a segment rack on the lower end of a cam operated throat slide actuating lever pivoted on the machine head, all as fully shown and described in said Letters Patent.

A fastener separator 22 is also mounted upon the throat carrier or slide 18 for operative movement therewith, the separator 22 being yieldingly connected to said slide so that on return movement of the slide the separator may move relatively to the slide in the event that it meets an obstruction 115 in the raceway.

The awl 20 is clamped in a two-part awl bar, the lower part 24 of the awl bar, which part receives the awl, having an adjustable toothed connection 26 with the upper awl 120

bar part 23. The awl bar part 28 is carried by an awl bar carrier 30 arranged to slide in a stationary bracket 32 on the machine head.

5 Movement of the awl bar carrier 30 along its guideway in the bracket 32 moves the awl 20 transversely of the line of fastening drive and in the line of shoe feed to effect step-by-step shoe feeding movement. This
10 shoe feeding movement of the awl bar 24, 26 and awl 20 is effected by a floating lever 34 provided at its upper end with a cam roll traveling in a cam groove in the rear face of a cam disk 36 mounted upon the
15 forward end of the main driving shaft 38. The awl bar 24, 26 is arranged to reciprocate vertically in its carrier 30 to form successive nail receiving openings in the work. To effect work penetrating movements of
20 the awl, the awl bar is provided on its rear face with rack teeth engaging correspondingly formed teeth 40 upon a segment rack carried upon one arm of a cam operated awl operating lever (not shown).

25 The parts above described conveniently may be and as shown are substantially like the corresponding parts of the machine of the above mentioned Letters Patent in construction and operation and reference
30 should be had to said Letters Patent for a more detailed description of the construction and operation of these parts.

The machine is herein illustrated (see Fig. 4) as operating on a shoe having the
35 outer sole A, the tap sole B, the upper C, in- sole D, and filling E.

The general operation of the machine as so far described may be summarized as follows: After a shoe has been mounted
40 upon the work support or horn 6 in the manner illustrated in Fig. 6, the horn is raised by an actuation of the work support controlling treadle (not shown) to press the work into engagement with a work abutment indicated generally at 42, the horn as it moves up into work clamping position assuming a position determined by the thickness of the work. After the machine has been started, the awl 20 is first moved
45 downwardly by its operating mechanism to form a fastening receiving opening in the work, the driver 10 at the same time being moved upwardly until it clears the throat 16. As the awl completes its work penetrating
50 movement, the horn 6 is depressed by the horn release mechanism to release the work from work clamping pressure against the abutment 42. The lever 34 is then actuated to move the awl laterally, through sliding
55 movement of the awl bar carrier 30, to feed the work over the horn until the fastening receiving opening which the awl has just formed in the work is brought into the line of drive beneath the driver, the throat 16 and separator 22 being withdrawn simul-

taneously during the work feeding movement whereby the throat 16 is moved out of the path of the awl 20. As the awl 20 returns to its initial position after the work feeding operation, the throat 16 and separator 22 are moved forwardly into their original positions, the throat 16 thereby being brought into operative position with the fastening passage therein in line with the driver and the separator acting to deliver a fastening to the throat 16 as the fastening receiving opening in the throat moves beneath the driver passage and as the driver completes its upward movement. Thereafter, the driver bar 8 is actuated by
70 its cam to effect a driving stroke of the driver 10 to insert the fastening which has just been delivered into the throat into the fastening receiving opening just formed in the work, the fastening being clenched in
75 the work by impact against the horn tip.

The abutment 42 is carried by the extension 43 of the guard plate 44 as shown most clearly in Fig. 7. The guard plate 44 is secured to the head 4 of the machine
80 by bolts 46 the heads of which are countersunk into the lower surface of the guard plate 44.

Means are provided for positioning the work relatively to the fastening inserting
85 instrumentalities in the form of a gage member 48 which lies flat up against the lower surface of the guard plate 44, and has the surface 49 arranged to engage the edge of the work. As shown most clearly in Fig. 100
90 4, the guard plate 44 extends forwardly of the gage member 48 and is formed to engage the upper marginal surface of the work at a point inside of the edge of the work.

95 The gage member 48 is secured to the guard plate 44 by bolts 50 which lie within recesses indicated at 52 formed in the upper surface of the guard plate 44 and extending only partially through the guard
100 plate. The bolts 50 pass through openings formed in the bottoms of the recesses 52 and through slots (not shown) in the gage member 48. The bolts 50 pass also through openings in a plate 54 which underlies the
105 gage member 48 and is held in frictional engagement therewith by the nuts 56 on the bolts 50 and by which the gage member 48 is frictionally held in any position of adjustment to which it may be moved by the
110 means now to be described. As illustrated, a rack 58 is provided on the gage member 48 and meshes with a pinion 60 on the shaft 62 which is journaled in the guard plate 44, as shown most clearly in Fig. 2. The shaft 62 is provided with a handle 64 for manipulation by the operator to effect the adjustment of the gage. The means above described for supporting and adjusting the gage member forms no part of the
115 120 125 130

present invention and any other supporting and adjusting means can be substituted therefor without departing from the essentials of the invention. In some of its aspects the invention is independent of the provision of any gage member or other work positioning means.

Novel means are provided for opening up the channel in advance of the fastening inserting instrumentalities to insure the proper operation of such instrumentalities in making a seam of metallic fastenings in the bottom of the channel. In the illustrated construction, such means comprises a channel opening finger 66 mounted on the guard plate 44, the plow-shaped end 68 of which normally occupies a predetermined position with relation to the plane defined by the driver 10 and awl 20 or, in other words, and as sometimes referred to hereinafter, the plane of operation of the fastening inserting instrumentalities.

The gage member 48 is so positioned relatively to the plane of operation of the fastening inserting instrumentalities that when a portion of the piece of work being operated upon, at which the edge of the work is at the minimum distance from the inner edge of the channel formed in the work, is in operative relation with the gage and the fastening inserting instrumentalities, the gage will so position the work that the inner edge of the channel will be located close to the plane of operation of the fastening inserting instrumentalities upon the work and the fastenings will be inserted in the channel of the work closely adjacent to the inner edge of the channel as indicated at 70 in Fig. 4 of the drawings. The plow-shaped end 68 of the channel opening finger 66 is positioned operatively to engage the channel of the work when the work is held in operative relation with the gage member 48 and the fastening inserting instrumentalities. When a portion of the work at which the distance between the edge of the work and the inner edge of the channel is greater than the minimum distance is presented to the gage member 48, the inner edge of the channel will be spaced farther away from the gage member 48 and from the plane of operation of the fastening inserting instrumentalities than when the inner edge of the channel is spaced at the minimum distance from the edge of the work. The distance from the edge of the work to the inner edge of the channel varies to a greater or less extent and it will be understood from the foregoing that if the channel opening finger 66 was stationarily mounted, the inner edges of the channel at the portions of the shoe where the distance between the edge of the shoe and the inner edge of the channel is the greatest would be moved away from the plow-shaped end 68 of the channel opening

finger, and effective operation of the finger in lifting or turning or laying back the lip of the channel out of the way of the fastening inserting instrumentalities would be prevented.

In order to cause the channel opening finger to be maintained invariably in operative relation to the lip of the channel so as to open the channel properly for operation of the fastening inserting instrumentalities, means are provided for yieldingly urging the channel opening finger 66 in a direction transverse to the plane of operation of the fastening inserting instrumentalities and toward the inner edge of the channel. In the illustrated construction, the finger 66 is mounted on the carrier 71 which slides in a groove 72 formed in a bracket 74 adjustably secured to the guard plate 44 by bolts 76 threaded into the guard plate 44 and passing through elongated slots 78 formed in the depending flange 80 of the bracket 74. The flange 80 is cut out at 81 so as to permit movement of the bracket 74 relatively to the shaft 62. The force by which the channel opening finger 66 is normally urged forwardly in the direction of the inner edge of the channel formed in the work is exerted by a spring 82 seated within the bore 84 of the carrier and abutting against the shoulder 86 of the set screw 88 which is threaded in the rear end of the bracket 74 and held in adjusted position therein by a lock nut 90. The set screw 88 forms a convenient means for adjusting the tension of the spring 82 and consequently the force with which the channel opening finger is urged forward by the spring. In operating on heavy, coarse work, a considerable force must be exerted to turn back the lip to expose the bottom of the channel for insertion of the fastenings. This force is so great that if an equal force were exerted in operating on relatively thin or delicate work, the edge of the plow-shaped end of the channel opening finger might be caused to cut or tear the lip of the channel or otherwise injure the work. By the means above described, however, the operator is enabled to readily adjust the force exerted on the channel opening finger to the character of the work being operated upon.

When no work is presented to the machine the plow-shaped end 68 of the channel opening device is projected beyond the plane of operation of the fastening inserting instrumentalities and to a distance from the work engaging surface of the gage member 48 greater than the distance between the edge of the work and the inner edge of the channel formed therein and is maintained in such position in opposition to the force exerted by the spring 82 by a set screw 92 threaded in the carrier 71 and passing through an elongated slot 94 formed in the bracket 74. The arrangement of the set screw 92 and

slot 94 is such that when the work is presented in operative relation to the gage 48, the channel opening finger will normally be pushed back to a position such that the set screw 92 will occupy substantially the middle portion of the slot 94 in consequence of which the channel opening finger will be permitted during operation on a piece of work to move in either direction from its normal position to accommodate itself to any change in the position of the inner edge of the channel relatively to the plane of operation of the fastening inserting instrumentalities resulting from movement of the work or a change in the distance between the edge of the work and the inner edge of the channel.

In order further to permit the channel opening finger to accommodate itself to the work so that it will be retained in the channel of the work and open the channel properly in advance of the operation of the fastening inserting instrumentalities, the plow-shaped end of the channel opening finger is permitted to move toward and from the work in a direction transverse to the plane of the work or, in other words, in a direction parallel to the plane of operation of the fastening inserting instrumentalities. As illustrated, the mechanism by which the result above set forth is obtained comprises a portion 96 depending from the carrier 71 and having journaled therein a stud shaft 98 upon which the channel opening finger 66 is pivotally mounted.

As most clearly shown in Fig. 6 of the drawings the channel opening finger 66 comprises a block 100 having bifurcated portions 102 and 104 extending therefrom, having formed therein openings 106 and 108 to receive the ends of the stud shaft 98. The channel opening finger 66 forms an extension of the bifurcated portion 102 of the block 100.

Means are provided for yieldingly holding the plow-shaped end 68 of the finger 66 down into the channel of the work. As shown, such means comprises a spring 110 coiled about the stud shaft 98 and having one end thereof engaging a pin 112 on the stud shaft and the other end engaging a pin 114 on the block 100.

In order that the force with which the plow-shaped end 68 of the channel opening finger 66 is held down into the channel of the work may be suited to the character of the work, means are provided for adjusting the tension of the spring 110. For this purpose the stud shaft 98 may be and, in the illustrated construction, is loosely mounted in the depending portion 96 of the carrier 72 so that it may be rotated therein and a set screw 116 is threaded into the depending portion 96 of the carrier and operates to retain the stud shaft 98 in any position of

angular adjustment to which it may be moved.

The movement of the finger 66 in a direction transversely of the plane of the work is preferably such as to permit the operative end of the finger to move downwardly relatively to the gage member 48 and the fastening inserting instrumentalities a sufficient distance to adapt itself to all the requirements of the work, for example the finger 66 will be moved downwardly when operating on the shank portion of a shoe sole. It is desirable, however, that the range of downward movement of the operative end of the finger be only such as is necessary to permit the end of the finger to follow the channel in all parts of the work since it is necessary in starting an operation on a piece of work to first engage the channel of the work with the plow-shaped end of the channel opening finger and then to raise the work into operative relation with the fastening inserting instrumentalities against the tension of the spring 110. The extent of upward movement required to be imparted to the work to bring it into operative position should be as little as possible, consistent with the proper operation of the finger, to save time and effort on the part of the operator. Means are therefore provided for limiting the extent of downward movement of the finger, which means as shown, comprises a set screw 118 passing through an opening formed in a split portion of the block 100, there being further a screw 120 passing through the split portion of the block 100 and operating to clamp the parts of said portion upon the set screw 118.

In order to adapt the channel opening device of this invention to the requirements of different kinds of work and to prolong the life of the channel opening device by permitting the substitution of a new channel opening finger when the finger is worn or otherwise rendered unfit for use, the bifurcated portion 102 of the block 100 has formed therein a socket 122 to receive the reduced portion 124 of the finger 66. A set screw 126 operates to retain the reduced portion 124 of the finger 66 in the socket 122. 115

The effectiveness of the operation of the channel opening finger is increased by positioning the plow-shaped end 68 of the finger closely adjacent to the path of movement of the awl 20. In order that no breakage may result if the channel opening finger is accidentally struck by the awl, the parts 102 and 104 of the block 100 are arranged to slide axially of the stud-shaft 98 against the force of the spring 110. 120

Figs. 7 to 10 inclusive illustrate a modification of the invention arranged for attachment to and movement with the awl bar carrier.

The channel opening device indicated gen- 130

erally at 128, is secured to the awl bar carrier 30, by a block 132 having a serrated surface formed thereon adapted to engage with a serrated surface formed on a depending part 134 of the awl bar carrier 30. The block 132 of the channel opening device is adjustably connected to the awl bar carrier 30 by a bolt 136 threaded into the depending part 134 of the awl carrier bar 30 and 10 passing through an elongated slot (not shown) in the block 132.

The operative parts of the channel opening device are supported by a bar 138 carried by the block 132 and bored out to receive 15 a stud shaft 140 rotatably mounted in the bore of the bar 138 and maintained in any position of angular adjustment relatively to said bar to which it may be moved, by the set screw 142 threaded into an opening in 20 the bar.

The channel opening finger 144 has a plow-shaped part 146 extending laterally therefrom and constructed and arranged to lie within the channel formed in the work 25 and to turn back the channel so as to expose the bottom of the channel for operation of the fastening inserting instrumentalities hereinbefore described.

The channel opening finger 144 is formed 30 with a reduced shank portion journaled in an enlarged portion 148 of a carrier 150 which, in turn, is rotatably mounted on the stud shaft 140.

It will be seen from the foregoing that the 35 plow-shaped end 146 of the channel opening finger 144 is mounted for movement in either of two directions. The fulcruming of the carrier 150 on the stud shaft 140 permits movement of the finger in a direction 40 transverse to the plane of the work, whereas the fulcruming of the shank of the finger 144 in the enlarged portion 148 of the carrier permits movement of the channel engaging portion 146 of the finger in a direction parallel to the plane of the work.

In order to hold the channel engaging portion 146 of the finger 144 down upon the work a spring 152 is coiled about the stud shaft 140 and is connected at one of its ends 45 to the pin 154 provided in an extension 156 of the stud shaft 140 and at its other end to a pin 158 formed in a part 160 rigidly connected to the reduced shank portion of the finger 144 by a nut 162. The member 160 50 normally engages the carrier at 164 (see Fig. 10) and the spring 152 operates through the member 160 to hold the channel engaging portion 146 of the finger 144 downward upon the work. The carrier 150 has formed 55 thereon the ears 166 and 168 journaled loosely on the stud shaft 140. Threaded into an extension 170 of the carrier 150 is an adjustable set screw 172 locked in adjusted position in the extension 170 of the carrier by a 60 lock nut 174 and engaging an extension 176

formed on the bar 138. The set screw 172 operates adjustably to limit the extent of the downward movement of the finger 144.

The mechanism hereinbefore described holds the channel engaging portion 146 of the channel opening finger against the inner edge of the channel in the work, the spring 152 yielding, however, to permit the member 160 to be moved away from the carrier 150 upon movement of the channel engaging portion 146 of the finger toward the work-engaging surface of the gage member 48. The engagement of the member 160 with the carrier serves to limit the movement of the finger 144 in a direction away from the gage member.

As heretofore explained, the plane of operation of the fastening inserting instrumentalities previously referred to herein is that defined by the awl and driver. In one of the appended claims, the fastening inserting instrumentalities are broadly defined as means for operating on the bottom of the channel formed in the work. As applied to a construction in which the means for operating on the bottom of the channel does not embody an awl and a driver, the reference in certain of the claims to the plane of operation of said operating means relates to a plane bearing a like relation to 90 the work and the other parts of the machine as that of the plane defined by the awl and driver in the machine in which the invention is herein illustrated as embodied.

Having thus described the invention, 100 what is claimed as new and desired to be secured by Letters Patent of the United States is:

1. In a machine of the class described, means for operating on the bottom of a 105 channel formed in the work, means for positioning the work relatively to said means having a surface to engage the edge of the work, said surface being spaced from the plane of operation of said means on the 110 work by a distance substantially equal to the minimum distance between the edge of the work and the inner edge of the channel, a channel opening device having its operative end spaced from the work engaging surface 115 of the work positioning means, and means for urging said device yieldingly in a direction transverse to the plane of operation of said operating means to cause said device to be maintained in contact with the inner edge 120 of the channel when the distance between the edge of the work and the inner edge of the channel is greater than the minimum distance between them in that piece of work.

2. In a machine of the class described, 125 means for operating on the bottom of a channel formed in the work, means for positioning the work relatively to said means having a surface to engage the edge of the work and being adjustable for different 130

- pieces of work to space said surface from the plane of operation of said means on the work by a distance substantially equal to the minimum distance between the edge of 5 the work and the inner edge of the channel, a channel opening device having its operative end spaced from the work engaging surface of the work positioning means, and means for urging said device yieldingly in 10 a direction transverse to the plane of operation of said operating means to cause said device to be maintained in contact with the inner edge of the channel when the distance between the edge of the work and the inner 15 edge of the channel is greater than the minimum distance between them in that piece of work.
3. In a machine of the class described, means for operating on the bottom of a 20 channel formed in the work, means for positioning the work relatively to said means having a surface to engage the edge of the work, said surface being spaced from the plane of operation of said operating means 25 on the work a distance substantially equal to the minimum distance between the edge of the work and the inner edge of the channel, a channel opening device having its operative end spaced from the work engag- 30 ing surface of the work positioning means, means for urging said device yieldingly in a direction transverse to the plane of operation of said operating means to cause said device to be maintained in contact with the inner edge of the channel when the distance 35 between the edge of the work and the inner edge of the channel is greater than the minimum distance between them in that piece of work, and means for adjusting the channel 40 opening device relatively to the work positioning means.
4. In a machine of the class described, means for operating on the bottom of a channel formed in the work, a device for 45 opening the channel in advance of the operation of said means, means for positioning the operative end of said device beyond the plane of operation of said means on the work, and means for maintaining said de- 50 vice normally in such position constructed and arranged to permit movement of said device by manipulation of the work having the channel thereof engaged with said device to a position substantially in the plane of 55 operation of said operating means.
5. In a machine of the class described, means for operating on the bottom of a channel formed in the work, work-positioning means engaging the edge of the work, 60 a movable channel opening finger having its operative end normally spaced from the work engaging surface a distance greater than the normal distance between the edge of the work and the inner edge of the chan- 65 nel formed therein so that the presentation of the work to the work-positioning means with the finger in the channel of the work effects movement of said finger, and means for urging said finger yieldingly in a direction opposite to that in which it is moved 70 by the work to permit the finger to be moved in one direction to maintain contact of the work with the work positioning means when a portion of the work, at which the distance between the edge of the work and the inner edge of the channel is less than the normal distance, is being operated upon by said operating means, and to cause the finger to be moved in an opposite direction when a portion of the work, at which the distance between the edge of the work and the inner edge of the channel is greater than the normal distance, is in operative relation to said operating means.
6. In a machine of the class described, 85 means for operating on the bottom of a channel formed in the work, and means constructed and arranged to lie in and turn back the lip of the channel to expose the bottom of the channel in advance of the 90 operation of said means, and being movable by manipulation of the work in a direction transverse to the plane of operation of said operating means.
7. In a machine of the class described, 95 means for operating on the bottom of a channel formed in the work, a stationary support, and a channel-opening device mounted loosely on the support for movement by manipulation of the work or to ac- 100 commodate itself to the character of the channel formed therein.
8. In a machine of the class described, means for operating on the bottom of a channel formed in the work, a stationary 105 support, a channel-opening device mounted loosely on the support, and means for urging said device yieldingly in a direction transverse to the plane of operation of said operating means.
9. In a machine of the class described, 110 means for operating on the bottom of a channel formed in the work, an abutment disposed for engagement with the channeled surface of the work, a stationary support, 115 and a channel-opening device mounted loosely on the support for movement of its operative end relatively to said abutment in a plane transverse to the channeled surface of the work and substantially parallel to 120 the plane of operation of said operating means, and for projection of said operative end to a point below the level at which the work is finally positioned for the operation of said operating means.
10. In a machine of the class described, 125 means for operating on the bottom of a channel formed in the work, an abutment disposed for engagement with the channeled surface of the work, a stationary support,

5 a channel-opening device mounted on the support for movement relatively to the abutment in a direction substantially parallel to the plane of operation of said operating means, and means for pressing said device against the work, constructed to yield during the functioning of the device to open the channel, thus permitting movement of the device with relation to the abutment 10 to accommodate itself to the configuration of the work.

11. In a machine of the class described, means for operating on the bottom of a channel formed in the work, a channel opening device constructed and arranged to turn back the lip of the channel in advance of the operation of said operating means, means for urging said device yieldingly in a direction transverse to the plane of operation of 15 said operating means, and means for regulating the force exerted by said yielding means.

12. In a machine of the class described, means for operating on the bottom of a channel formed in the work, a stationary support, a channel-opening device mounted loosely on the support for movement in a direction transverse to the plane of operation of said operating means, and means for 20 limiting the extent of movement of said device.

13. In a machine of the class described, means for operating on the bottom of a channel formed in the work, a stationary support, a channel-opening device mounted loosely on the support, controlling means for said device constructed and arranged to permit the device to be moved in opposition to said controlling means by manipulation 30 of the work, and means for limiting the extent of movement of said device under the operation of said controlling means.

14. In a machine of the class described, a frame, and a channel opening finger designed to turn the channel flap away from the edge of the sole and mounted loosely on the frame and movable relatively thereto in either of two directions transverse to each other to accommodate itself to the shape of 50 the work and the position of the channel relatively to the edge of the work.

15. In a machine of the class described, means for operating on the bottom of a channel formed in the work, and a channel 55 opening device for opening the channel for operation of said means movable in either of two directions to accommodate itself to the character of the work.

16. In a machine of the class described, 60 a sliding carrier, a channel opening device pivoted on the carrier and operative to turn the channel flap away from the edge of the sole, and means for yieldingly controlling said device.

17. In a machine of the class described, a

sliding carrier, a channel opening device pivoted thereon, means for yieldingly controlling said device, and adjustable means for limiting the extent of movement of said device constructed and arranged to abut 70 against said carrier.

18. In a machine of the class described, a movable carrier, yielding means for moving said carrier in one direction, a channel opening device pivoted in the carrier and designed to lift the channel flap away from the edge of the sole, and yielding means for moving the operative end of said device in a direction transverse to the direction of movement of the carrier. 75

19. In a machine of the class described, a movable carrier, means for limiting the extent of movement of the carrier, a channel opening device designed to lift the channel flap away from the edge of the sole and mounted loosely on the carrier for movement relatively to the carrier, and means for limiting the extent of such movement of the channel opening device. 80

20. In a machine of the class described, 90 a work abutment, a carrier movable with respect to the abutment, a stud-shaft fixed in said carrier, and a channel opening device mounted for pivotal and sliding movement on said stud-shaft.

21. In a machine of the class described, a carrier, a stud-shaft fixed in said carrier, a channel opening device mounted for pivotal movement on said stud-shaft, a spring connected to the stud-shaft and channel 100 opening device and operating to urge said device yieldingly in the direction of the work, and means for securing said stud in various positions of angular adjustment in said carrier to regulate the tension of said 105 spring.

22. In a machine of the class described, fastening inserting mechanism comprising a reciprocating member operative on the bottom of a channel formed in the work, a channel-opening finger mounted adjacent to the path of movement of said member, and means for urging said channel opening finger yieldingly toward the path of movement of said member. 110

23. In a machine of the class described, fastening inserting mechanism comprising an awl movable in a predetermined path, a channel opening finger mounted adjacent to said path, yielding means for maintaining 120 said finger normally in a predetermined position relatively to the path of movement of said awl constructed and arranged to permit movement of the finger away from the path of the awl if struck by the awl.

24. In a machine of the class described, a work support, means for operating on the bottom of a channel formed in the work, a fixed member, a universally tiltable work abutment mounted on said member, and a 130

channel opening device stationarily mounted relatively to said member.

25. In a machine of the class described, means for operating on the bottom of a channel formed in the work, means for positioning the work relatively to said operating means having a surface to engage the edge of the work, and a channel opening de-

vice normally occupying a certain position with respect to the work positioning means 10 and movable by manipulation of the work in a direction transverse to the work-engaging surface of the work-positioning means.

In testimony whereof I have signed my name to this specification.

FRED L. MACKENZIE.
